UNITED STATES PATENT OFFICE.

MAXIMILIAN E. BUHSE, WALTER W. BUHSE, ALEXANDER F. BUHSE, AND HENRY L. BUHSE, OF MINNEAPOLIS, MINNESOTA.

CANDY-PULLING MACHINE.

1,132,556.

Specification of Letters Patent. Patented Mar. 23, 1915.

Application filed February 16, 1911. Serial No. 608,953.

To all whom it may concern:

Be it known that we, MAXIMILIAN E. BUHSE, WALTER W. BUHSE, ALEXANDER F. BUHSE, and HENRY L. BUHSE, citizens of the United States, residing at Minneapolis, in the county of Hennepin and State of Minnesota, have invented certain new and useful Improvements in Candy-Pulling Machines; and we do hereby declare the following to be a full, clear, and exact description of the invention, such as will enable others skilled in the art to which it appertains to make and use the same.

Our invention relates to candy pulling machines and has for its special object the provision of a highly efficient machine of this character.

To the above ends the invention consists of the novel devices and combinations of 20 devices hereinafter described and defined in the claims.

In the accompanying drawings, which illustrate the invention, like characters indicate like parts throughout the several views. Referring to the drawings: Figure 1 is a plan view of the improved machine, some parts being broken away and some parts being sectioned; Fig. 2 is a side elevation of the machine, with some parts broken away 30 and with some parts sectioned; Fig. 3 is a transverse vertical section taken approximately on the line $x^3 x^3$ of Fig. 2, some parts being broken away; Fig. 4 is a fragmentary view in longitudinal section taken approximately on the irregular line $x^4 x^4$ of Fig. 3; and Figs. 5 to 11 inclusive are diagrammatic views illustrating the different pulling movements produced in the candy during the pulling action.

The machine illustrated in the drawings is a double machine adapted to pull two batches or hanks of candy at one time, whether of the same or of different flavors, but it will of course be understood that the same principles of construction may be incorporated in a single machine.

The body 1 of the machine frame is, as shown, a regular cast box-like structure supported by legs 2, and the said legs at each 50 side of the machine preferably support wood working-tables 3.

The pulling device at each side of the machine comprises a relatively fixed pulling pin 4 and a pair of movable pulling pins 5.

The fixed pulling pins 4 are rigidly secured 55 to the forwardly extended ends of a cross bar 6 that is rigidly secured to what may be treated as the front end of the frame 1. The movable pins 5 are rigidly secured to the ends of crank bars or heads 7 rigidly 60 secured at their intermediate portions to a transversely extended shaft 8. This shaft 8 is mounted to rotate in bearings 9 of a traveling carriage 10, which latter is mounted for horizontal sliding movements longitudinally of the machine in elongated runways 11 formed in the upper side portions of the frame body 1. The shaft 8 is preferably arranged with its axis in a horizontal plane of the fixed pulling pins 4, and the 70 crank heads 7 carried by the ends thereof are ranged inward of the inner ends of the said pins 4 so that the said shaft 8 may be moved into axial alignment with the said pins 4. 75

Rigidly secured to the bottom of the carriage 10 is a pair of rack bars 12 having teeth on their outer faces. Pinions 13 mesh with the rack bars 12 and with outer rack bars 14 that are fixed on the sides of the 80 frame body 1. These pinions 13 are journaled to a cross head 15 that is supported by and has threaded engagement with a long screw shaft 16. The screw shaft 16 extends centrally and longitudinally of the frame 85 body 1 and is journaled in suitable bearings 17—18—19 on the end portions of said frame body, and is held against endwise movements by the said bearings. At the rear end of the machine the screw shaft 16 is provided with an intermediate pulley 20 that is fixed thereto, and at the front and rear thereof with loose pulleys 21 and 22. Two belts not shown will be arranged to normally run one over each of the loose pulleys 95 21 and 22 and these belts will run through the looped arms 23 of a belt shifter comprising also a pivoted cam acting shipper head 24 supported by frame body 1. This belt shifter is of the ordinary type used in connection with planers, and for the purposes of this case it is only necessary to state that when the shipper head 24 is moved in one direction from the position shown in Fig. 1, one of the belts will be run onto the intermediate pulley 20 and when the said head is moved in the other direction from its 100 said normal or intermediate position the 105

other belt will be moved onto the said pulley 20. In this way reverse rotative movements may be imparted to the screw shaft 16.

The belt shifter above described is operated by the traveling carriage 10 and as shown this is accomplished through a long shipper bar 25 that is mounted to slide endwise through bearings 26 on one side of the frame body 1. The carriage 10 is provided with a shipper lug 27 having a perforation through which the bar 25 works loosely. For coöperation with the shipper lug 27 the bar 25 is provided on each side thereof with collars 28 adjustably secured on the said bar 25 by set screws 29.

The adjustment of the collars 28 on the bar 25 determines the extreme traveling movements of the carriage 10. The front collar 28 should be so adjusted that the shaft 8 will be in approximate alinement with the fixed pulling pins 4 at the extreme forward movement of the carriage. The rear collar 28 will be set in different positions on the bar 25 according to the amount of movement that it is desired to give to the carriage 10.

Loosely journaled on the intermediate portion of the crank carrying shaft 8 is a spur gear 30 that meshes with a rack bar 31 secured to the top plate of the frame body 1. The gear 30 carries one or more spring pressed pawls 32 that engage with a ratchet toothed hub 33, rigidly secured to the shaft 8 adjacent to the said wheel. This pawl and ratchet device 32-33 will cause the crank shaft 8 and its crank 7 to rotate when the carriage 10 is moved forward or toward the fixed pulling pins 4, but permit the said shaft and its cranks to be held against rotation when the said carriage 10 is given its reverse or return movement toward the rear of the machine.

As is evident when the screw shaft 16 is rotated, it will move the cross head 15 in the one direction or the other, according to the direction of rotation of said shaft, and through the pinions 13 carried by the said cross head, the carriage 10 will be moved in the same direction as the cross head, but at twice the rate of speed. As otherwise stated, the carriage will move always in the same direction as the cross head, but will be given twice as much movement as the cross head in a direction longitudinally of the machine.

In the diagrammatic views Figs. 5 to 11 inclusive the hank or drawnout soft bar of candy is indicated diagrammatically by the character *y*. The hank of candy is first applied to the pulling pins 4 and 5 substantially as shown in Fig. 5, either while the said pins are separated as shown or while they are moved closer together. At any rate, when the carriage 10 first reaches its extreme rearmost position after the candy 65 has been applied to the pulling pins the

hank will be drawn out approximately as shown in Fig. 5. Then when the carriage begins its forward movement the cranks 7, which carry the pins 5 will commence to rotate and will continue their rotary movement throughout the forward movement of the carriage and until the crank shaft 8 is moved forward approximately into alinement with the fixed pins 4. Figs. 6, 7, 8 and 9 illustrate progressively the operation of 75 the revolving pins 5 during the forward movement of the carriage, and Fig. 10 shows the relative positions of the three pulling pins at a time when the carriage has reached its extreme forward movement and is just 80 ready to begin its return movement.

Fig. 11 illustrates the drawing action on the hank when the carriage is given its return movement while the cranks and the pins 5 remain stationary in respect to the 85 said moving carriage 10. When the carriage is again moved forward the revolving movements of the pins 5 will again be repeated and the hank will be again wound up. This combined winding and pulling action insures thorough mixing of the candy, 90 thorough aerating thereof, and generally stated a very high grade of work.

The means for varying the length of stroke or traveling movement of the carriage of the machine is of very great importance, because it adapts the machine to handle candy of various degrees of hardness. Hard candies will not stand being pulled out to as great length as the softer 100 candies and furthermore the length to which the candy hank should be pulled will also depend somewhat on the size thereof. This machine is universally adaptable to all of these conditions and the amount of rotary 105 movement given to the cranks will always be proportionate to the length of travel of the carriage and will be sufficient in all cases to wind up the stretched hank when the carriage is moved toward the relatively fixed 110 or local pulling pin. The expression, "local pulling pin", does not necessarily mean that the said pin has no movement whatever, but it means that the pin occupies a certain position in respect to the pins carried by the 115 traveling carriage and the cranks thereof, so that in one position of the carriage the pins on the rotating crank may travel around said local pin.

As already indicated, with the double machine candies of different flavors may simultaneously or successively be pulled on the machine without requiring the cleaning of previously used pulling pins or pegs. The term "pulling pins" is used in a broad sense 125 to include any kind of projections that are adapted to directly engage with the candy hank in the pulling action.

What we claim is:

1. In a candy pulling machine, the com- 130

bination with a local pulling pin, of a carriage mounted to move toward and from said local pulling pin, adjustable means for imparting variable traveling movements to the said carriage, a crank mounted on said carriage and provided with oppositely disposed pulling pins, and means for rotating said crank when said carriage is moved toward said pulling pin, which crank operating means is inoperative when the said carriage is moved away from said local pulling pin.

2. In a candy pulling machine, the combination with a local pulling pin, a carriage and means for moving said carriage toward and from said local pin, of a crank mounted on said carriage and provided with diametrically offset pulling pins, and means for rotating said crank to wind up the candy on the pins thereof, when the said carriage is moved toward said local pin, the said means comprising a pawl and ratchet device, whereby the said cranks are not rotated when the said carriage is moved away from said local pulling pin.

3. In a candy pulling machine, the combination with a local pulling pin, a carriage and means for moving said carriage toward and from said local pin, of a shaft mounted on said carriage and provided with a crank head having diametrically offset pulling pins, a gear loosely mounted on said shaft, a relatively fixed rack engaging said gear, and a pawl and ratchet connection between said gear and shaft arranged to cause said cranks to rotate only when the said carriage is moved toward said local pin.

4. In a candy pulling machine, the combination with a frame body and a pair of local pulling pins supported from the opposite sides thereof, of a carriage mounted to travel on said frame toward and from said local pins, means for reciprocating said carriage, a shaft mounted on said carriage, crank heads on each end of said shaft each having a pair of diametrically offset pulling pins; means actuated by the traveling movement of said carriage, for rotating the said shaft when said carriage is moved toward said local pins, the said means comprising a gear loose on said shaft, a rack secured to said frame and engaging said gear, and a pawl and ratchet connection between said gear and shaft.

5. In a candy pulling machine, the combination with a local pulling pin, of a carriage mounted to travel toward and from said pin, means for imparting traveling movement to said carriage, a crank mounted on said carriage and having oppositely disposed pulling pins, and means for operating said crank, operative thereon only when said carriage is moved toward said local pulling pin.

6. In a candy pulling machine, the com-

bination with a local pulling pin and a carriage mounted to travel toward and from the same, a crank mounted on said carriage and having oppositely disposed pulling pins, means for rotating said crank when said carriage is moved toward said local pulling pin, connections including a screw shaft for imparting traveling movements to said carriage, a reversible drive for reversibly rotating said screw shaft, and means controlled by the movements of said carriage for automatically reversing the action of said reversible drive.

7. In a candy pulling machine, the combination with a local pulling pin and a carriage mounted to travel toward and from the same, a crank mounted on said carriage and having oppositely disposed pulling pins, means actuated by the traveling movement of said carriage, for rotating said crank when said carriage is moved toward said local pulling pin, connections including a screw shaft for imparting traveling movements to said carriage, a reversible drive for reversibly rotating said screw shaft, means controlled by the movements of said carriage for automatically reversing the action of said reversible drive, the said means being adjustable to vary the distance of travel of said carriage.

8. In a candy pulling machine, the combination with a frame and a local pulling pin supported thereby, of a carriage mounted to travel on said frame toward and from said local pin, a crank mounted on said carriage and having offset pulling pins, means actuated by the traveling movement of said carriage, for rotating said crank when said carriage is moved toward said local pulling pin, means including a screw shaft for imparting traveling movements to said carriage, a reversible drive for reversibly rotating said screw shaft, means for automatically reversing the action of said reversible drive, comprising a sliding bar supported by said frame, longitudinally spaced abutments on said bar, and an abutment carried by said carriage and alternately engageable with the abutments on said bar to limit the movements of said carriage.

9. In a candy pulling machine, the combination with a local pulling pin, of a carriage mounted to move toward and from said local pulling pin, a crank carried by said carriage and provided with oppositely disposed pulling pins, and means for completely rotating said crank while said carriage is being moved toward said local pulling pin, which means is inoperative when the carriage is moved away from said local pulling pin.

10. In a candy pulling machine, the combination with a local pulling pin and carriage, of adjustable means for imparting variable traveling movements of said carriage toward and from said local pulling

pin, a crank mounted on said carriage and having oppositely disposed pulling pins for coöperation with said local pulling pin, and means actuated by the traveling movement of said carriage for completely rotating said crank, to thereby wind up the candy, when said carriage is moved toward said pulling pin.

11. In a candy pulling machine, the combination with a local pulling pin, of a carriage mounted to move toward and from said local pulling pin, adjustable means for imparting variable traveling movements to the said carriage, a crank mounted on said carriage and provided with oppositely dis-

posed pulling pins, and means actuated by the traveling movement of said carriage, for completely rotating said crank when said carriage is moved toward said pulling pin to thereby wind up the candy.

In testimony whereof we affix our signatures, in presence of two witnesses.
